UNITED STATES PATENT OFFICE.

GEORGE T. BUDDLE, OF CHICAGO, ILLINOIS.

COMBINED TABLE LOCK AND OPENER.

1,156,460.

Specification of Letters Patent.

Patented Oct. 12, 1915.

Application filed October 19, 1914. Serial No. 867,428.

To all whom it may concern:

Be it known that I, GEORGE T. BUDDLE, a citizen of the United States, residing at Chicago, in the county of Cook and State of Illinois, have invented a new and useful Combined Table Lock and Opener, of which the following is a specification.

This invention relates to locks for use in connection with extension tables and is more particularly designed as an improvement upon the structure disclosed in Patent No. 1,103,029, issued to me on July 14, 1914.

One of the objects of the invention is to provide a lock which, when operated in one direction, will successively engage a keeper and draw together the sections of the extension table, holding them in such position and which, when actuated in the opposite direction, will operate to push the sections of the table apart and to then release one of the sections.

A further object is to provide a combined lock and opener of this type which is compact, can be operated readily, and which is formed of the minimum number of parts.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

In the accompanying drawings the preferred forms of the invention have been shown.

In said drawings: Figure 1 is a bottom plan view of a portion of an extension table having the present improvements combined therewith, the sections of the table being shown drawn together. Fig. 2 is a view similar to Fig. 1 but showing the relative positions of the parts after one of the sections has been pushed from the other section and released from the lock. Fig. 3 is a view similar to Fig. 1 but showing a modified construction. Fig. 4 is a view showing the parts illustrated in Fig. 3 shifted to unlocked position. Fig. 5 is a bottom plan view of another modified form of lock and opener. Fig. 6 is a bottom plan view of another modified structure. Fig. 7 is a bottom plan view of a further modification.

Referring to the figures by characters of

reference A and B designate opposed sections of an extension table and it is designed to attach one part of the present invention to the bottom of one of these sections and another part to the bottom of the other section so that, when the parts are properly actuated, the sections will be either drawn toward each other and locked or pushed apart, as desired.

One form of keeper to be used has been illustrated in Figs. 1, 2 and 5 and consists of a base or attaching plate 1 provided, at one end, with a lug 2 disposed at right angles to the base, this lug being cut away at one end so that the base plate 1 projects laterally beyond the lug as shown at 3. The plate 1 is adapted to be fastened to the table by means of screws or like fastening means as shown in Figs. 1 and 2 or, if preferred, can be adjustably attached to the section A. Where it is designed to attach the keeper adjustably, the base plate 4 of the keeper is formed with spaced longitudinal slots 5 and pivotally connected to the plate 1 at a point between the slots is a disk 6 having eccentrically disposed slots 7 through which extend attaching screws 8, these screws projecting through the slots 5 and engaging the section A. By loosening the screws, the disk 6 can be rotated so as to cause said disk and the keeper to shift toward or from the section B after which, by tightening the screws 8, the parts will be held securely in the positions to which they have been adjusted.

One form of latch adapted to be used in connection with the keepers has been illustrated in Figs. 1 and 2 and includes a latch strip 9 pivotally connected at one end, as shown at 10, to a lever 11 which, in turn, is pivotally mounted on an attaching plate 12 adapted to be secured to the section B. The other end of the strip 9 is provided, at its free end, with a hook 13 formed by producing a rectangular notch 14 in the strip 9 near its end and by reducing the width of the terminal portion of the strip 9. A longitudinal slot 15 is formed in the strip 9 adjacent the hook 13 and projecting thereinto is a guide stud 16 projecting from an attaching plate 17 which is secured to the section B. That end of slot 15 nearest the lever 11 is extended diagonally for a short distance as shown at 18.

The parts are so proportioned that when the lever 11 is swung in the direction indi-

cated by the arrow in Fig. 1, it will slide the strip 9 toward the section A, thus removing the hook 13 from engagement with lug 2 and causing the wall of notch 14 to come against said lug 2 and push against it, thus thrusting the section A away from section B. After the two sections have been moved apart a short distance, the diagonally disposed slot 18 will receive the guide stud 16 and cause the strip 9 to swing laterally to the position shown in Fig. 2, thus removing hook 13 from engagement with the lug 2 and allowing section A to be pulled away from section B.

When it is desired to place the sections A and B together and lock them in such position, the section A is shoved toward section B until the lug 2 comes against the shoulder 14 after which handle 11 is swung in a direction opposite to that indicated by the arrow in Fig. 1. During the first portion of this movement the walls of the diagonal slot 18 will engage the stud 16 and swing strip 9 laterally so that hook 13 will move into engagement with lug 2. Further movement of the lever will cause the strip 9 to be drawn longitudinally, thus carrying the section A with it. As the lever 11 passes its dead center, it comes against a stop lug 19 formed on the plate 12 so that movement of the lever and the strip is thus limited and the parts are locked together.

Instead of depending upon the shoulder 14 to engage the lug 2 and push the sections apart, a supplemental lug 20 can be formed upon the base plate of the keeper as shown in Fig. 7 and, when the strip 21, which corresponds with strip 9, is shifted longitudinally, the hook 22 will press against lug 20 and push the sections A and B apart. Thus in this modified form of device the strain upon the keeper is distributed between two lugs, the pulling strain being transmitted through the lug 23 which corresponds with lug 2, while the pushing strain is transmitted through lug 20. Instead of forming the lugs with the keeper engaging portion integral with the latch strip, said keeper engaging portion can be made in a separate piece as shown, for example, in Figs. 3 to 6 inclusive.

By referring to Fig. 3 it will be seen that the same utilizes a latch strip 24 similar to the strip 9 with the exception that it is not provided with a hook. Instead a keeper engaging member 25 is pivotally mounted on the strip as shown at 26 and has one end projecting beyond the end of strip 24 and provided with a hook 27. This member 25 has a longitudinal slot 28 merging into a diagonally disposed slot 29, the longitudinal slot registering with the corresponding slot in the strip 24 while the diagonal slot 29 diverges from the corresponding diagonal slot in the strip 24. A stud 30 extends from

the attaching plate 31 and into both of the slots in strip 24 and member 25. Thus it will be seen that when the lever 32 is actuated for the purpose of releasing the section A, the hook 27 will move out of engagement with lug 33 while the end of the strip 24 will then come against the lug 33 and push the section A away from the section B. This operation occurs while the stud 30 is located within the longitudinal slots. As soon as said stud enters the diagonal slots within the strip 24 and member 25, the said strip 24 is swung quickly in one direction, while the member 25 is swung at the same time in the opposite direction so that the parts assume the position shown in Fig. 4. Consequently, while the member 24 continues to push against the lug 33, the hook 27 is swung quickly out of engagement with the lug. In assembling the parts of the table the foregoing operation is reversed.

Instead of pivotally mounting the member 25 at that end thereof remote from its hook 27, the pivot can be located between the hook and the slots, as shown at 34 in Fig. 5. In this structure the operation is the same as that before described with reference to Figs. 3 and 4 with the exception that the relative movement of the hook and the strip 35 is not so great.

Instead of mounting the strip 35 so as to press against the lug 33, a finger 36 can be extended from the strip 37 and beyond the hook 38 on the keeper engaging member 39 and the latch can then be used in connection with a keeper such as illustrated in Figs. 6 and 7. With this construction, the strip 37 is provided with a slot which is straight from end to end as shown at 40, while the keeper engaging member 39 has a longitudinal slot 41 merging into a diagonal slot 42. Thus when the stud 43 enters the far ends of the slots, the strip 37 pushes forwardly against the lug 20 while the hook 38 is swung laterally out of engagement with lug 23. The operation of the device shown in Fig. 6 corresponds with that of the device shown in Fig. 7 in that the lug 20 receives the thrusting strain while the lug 23 receives the pulling strain.

Various changes other than those described and illustrated may be made as will be obvious.

In order that the strips 9, 24 or 37 may be made of light thin material, each of said strips is preferably offset at a point between its ends so that the two end portions will lie in parallel planes, and at the same time allow for the difference in distances between the section B and the two end portions of the strips. The bend resulting in this offset has been indicated in each of the figures at 44.

What is claimed is:—

1. The combination with a keeper, of a 130

guide, a member slidably engaging the guide, means for shifting the slidable member in one direction to push against the keeper, a keeper engaging latch pivotally connected to the slidable member, and means on the latch and movable against the guide during the pushing movement of the slidable member, to shift the latch out of engagement with the keeper, and, during the opposite movement 10 of the slidable member, to shift the latch into engagement with the keeper.

2. The combination with a keeper, of a latch strip having a longitudinal slot merging at one end into an obliquely disposed slot, 15 a guide member extending into said slot, means for shifting the latch strip in one direction to thrust against the keeper while the guide member is within the longitudinal slot, and to disengage the latch strip from 20 the keeper while the guide member is within the obliquely disposed slot, a hooked member pivotally connected to the latch strip, and adapted to engage the keeper to pull thereon during the movement of the latch 25 strip in the opposite direction, said hooked member having a longitudinal slot merging at one end in an obliquely disposed slot, the guide member extending into the slot.

3. The combination with a keeper having 30 a projecting portion, of a latch strip having a longitudinal slot merging at one end into an obliquely disposed slot, a fixed guide stud extending into the slot, means for shifting the latch strip in one direction to thrust

against the projecting portion of the keeper 35 while the guide stud is in the longitudinal slot and to disengage the latch strip from the keeper when the stud is in the obliquely disposed portion of the slot, a hooked member pivotally mounted on the guide stud and 40 having a longitudinal slot merging at one end into an obliquely disposed slot, said guide stud projecting into the slot in said hooked member, said hooked member constituting means for engaging the projecting 45 portion of the keeper.

4. The combination with a keeper having a projecting portion, of a guide member, a latch strip having a longitudinal slot into which the guide member extends, means for 50 sliding said latch strip longitudinally to thrust against the keeper, and a keeper engaging hook movable with the latch member and having a longitudinal slot merging at one end into an obliquely disposed slot, said 55 guide member extending into the slot and co-operating with the walls thereof to shift the hook laterally out of engagement with the keeper during the pushing operation by the latch strip.

In testimony that I claim the foregoing as my own, I have hereto affixed my signature in the presence of two witnesses.

GEORGE T. BUDDLE.
